ADJUSTABLE DISH HOLDER

Pieter Kant, Kort Ambachtlaan 22,
Zwijndrecht, Netherlands

Filed Feb. 16, 1971, Ser. No. 115,919

Term of patent 14 years

Int. Cl. D7—99

U.S. Cl. D44—10 B

FIG.1

FIG.4

FIG. 1 is a top perspective view of an adjustable dish holder showing my new design;

FIG. 2 is a top plan view thereof;

FIG. 3 is a side elevation thereof opposite that shown in FIG. 1; and

FIG. 4 is an end elevation thereof opposite that shown in FIG. 1.

I claim:

The ornamental design for an adjustable dish holder, as shown.
